UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

RELAY.

1,424,346.

Specification of Letters Patent. Patented Aug. 1, 1922.

Application filed March 14, 1919. Serial No. 282,544.

To all whom it may concern:

Be it known that I, JOHN ERICKSON, a citizen of the United States of America, and a resident of Chicago, county of Cook, and 5 State of Illinois, have invented certain new and useful Improvements in Relays, of which the following is a specification.

My invention relates to electromagnetic circuit closing services and more particularly 10 to a relay especially but not exclusively adapted to use with alternating current.

One of the objects of my invention is to provide an improved relay which will operate with either direct or alternating current 15 without requiring special adjustments when used with a particular current.

Another object is to provide a relay which, when energized by alternating current, will operate in a manner practically eliminating 20 all undesirable buzzing of the armature due to the reversals of current, and also what is of more importance, the possibility of periodically opening the contacts when reversals of current occur.

25 My invention is adapted to various uses, for instance, in a circuit where a relay is required to operate at one time with alternating current and at another time with direct current. It also provides an efficient relay 30 for use wherever an alternating current relay only is required.

The foregoing and other useful objects of my invention will be hereinafter more particularly set forth and claimed.

Referring to the accompanying drawings:

Fig. 1 shows a top view of the relay of my invention.

Fig. 2 shows a side view of the above relay.

40 Fig. 3 shows a front view of the above relay.

Fig. 4 shows a top view of my relay in operated position.

Fig. 5 shows a sectional bottom view of the relay in which the section is taken 45 through the center of the core.

Fig. 6 shows an improvement of the same relay.

Fig. 7 shows a top view of said improvement.

50 I will now describe my invention more in detail.

In Figs. 1, 2, 3, 4 and 5 I have shown a coil mounted on an iron heel piece 2, the latter forming part of the magnetic circuit. The 55 armature 3 is also mounted on this heel piece

by means of the hinge 4. A purpose of hinge 4 is to provide a pivot for arm 5 (Figs. 1 and 2) enabling it to close contact points on springs 6 and 7 when armature is attracted due to the energization of the coil. Attached 60 to the extremity of armature 3, by another hinge 8, I have shown a roller combination 9, which is kept in contact with spool head 10, which may be of any non-magnetic material, preferably brass, by means of spring 11. This 65 spool head is made flush with core 12, as shown in Fig. 5. Providing the relay is in its normal, deenergized state, the path for the magnetic flux is now complete with the exception of a break at point 13, the significance of which will be pointed out later.

Due to tension in spring 6 transmitted to arm 5, the armature is normally held back as shown in Fig. 1, but is prevented from going too far back by stop 14. It may be 75 added here that the position of this stop determines the distance between roller 15, and the end of the core (Fig. 5). The construction of the relay is such that roller 15 can pass a certain distance beyond the point 80 of maximum pull before the armature strikes spoolhead 10, at 16 to avoid rebound. This is an important point of my invention and will be discussed more fully in another part of the specification.

85 The operation of the relay is as follows: The current is led into the coil by way of the terminals 17 and 18 (Fig. 2), thus magnetizing the core and consequently attracting roller combination 9 causing arm 5 90 to close contacts on springs 6 and 7. Roller 15 will be attracted to the point of maximum pull, but due to inertia will pass slightly beyond that point but yet not enough to allow armature 3 to strike the spoolhead, 95 thus eliminating the objectional rebound. The roller provides a free movement across the pole piece by reducing friction.

Fig. 4 illustrates what I have explained in the case of the relay energized, showing 100 the roller in attracted position holding contacts on springs 6 and 7 closed.

Figs. 6 and 7 show two views of improvements on the same relay, merely showing an improved armature hinge and an improved roller combination, the principle of the invention remaining unchanged.

In these Figures 6 and 7 a thin sheet of spring steel 19 is used to fasten the armature 20 to the heel piece 21 by means of screws 110

22. In this construction I provide reinforcing lugs 23 on the armature and lugs 24 on the clamp 25. These lugs are provided to protect the hinge against torsional strain.
- 5 Another feature shown is an improved hinge for the roller or armature. Part 26 is of spring brass or other suitable material and has three tongues bent as shown in Figs. 6 and 7. The center tongue is shaped and 10 exerts tension in such a way as to keep roller 27 in light contact with spoolhead 28 at all times. Pin 29 extends through part 30 of roller combination and fits into a slot cut in extremity of armature 20 as plainly shown 15 in Fig. 7. Outside tongues of part 26 exert a pressure sufficient to hold pin 29 in slot, thus attaching the roller combination to the armature 20. In order to remove the roller combination from the armature, all that 20 is necessary is to press the pin against the two outside tongues, clear of the slot, and pull away from the coil in a direction parallel to the armature.
- Having fully described my invention, 25 what I consider to be new and desire to have protected by Letters Patent will be more specifically pointed out in the appended claims.
- What I claim as my invention is:
- 30 1. In a relay, a magnet, an armature and a heel piece for said magnet, said armature mounted on said heel piece solely by means of a flexible spring, and a roller on said armature which roller is magnetically attracted to move said armature, said spring reinforced by a lug on the armature and another lug on the heel piece.
2. In a relay, a magnet, an armature and a heel piece therefor, said armature pivoted 40 to the heel piece solely by means of a flexible spring which permits said armature to be operated to close its contacts, and a roller on said armature which roller is magnetically attracted to move said armature, said spring reinforced by a lug on the armature and another lug on the heel piece.
3. In a relay having a magnet and a heel piece, an armature for the magnet having a roller which is attracted by the core of said magnet to close a circuit, said armature mounted on said heel piece by means of a flexible spring, said spring reinforced by a lug on the armature and another lug on the heel piece.
- 50 4. In a relay having a magnet and a heel piece, an armature for the magnet having a roller which is attracted by the core of said magnet to close a circuit, said armature mounted on said heel piece by means of a flexible spring, said spring reinforced by a lug on the armature and another lug on the heel piece.
- 55 a roller which is attracted by the core of said magnet to close a circuit, said armature mounted on said heel piece by means of a flexible spring, said spring reinforced by a lug on the armature and another lug on the heel piece, the lug on the heel piece so placed as to prevent movement of the armature relative to the heel piece in one direction and the lug on the armature preventing movement in the other direction.
- 60 5. In a relay comprising a magnet, a heel piece, an armature pivoted on said heel piece by means of a flexible spring which acts as the pivot of said armature and permits said armature to be attracted by the magnet, the provision of protecting lugs part attached to the armature and part to the heel piece of the relay and all projecting over the joint formed by said spring said lugs so placed as 65 to protect said spring joint and prevent tearing or breaking of said spring.
6. In a relay, a magnet, an armature therefor, a guiding surface for said armature, a roller on said armature, a spring for said armature to cause said roller to always engage said surface, said surface consisting of a non-magnetic surface extending over a part of and flush with another part of a magnetic surface, said magnet adapted to magnetize 80 said magnetic surface to cause said armature to roll over said non-magnetic surface and into engagement with said magnetic surface, and springs directly controlled by said armature to close a pair of contacts, said 85 springs also operating to restore said armature upon deenergization of said magnet.
7. In an alternating current relay, an iron core, an L shaped heel piece having one leg attached to one end of said core and the other leg extending parallel to said core, contact springs mounted on said heel piece, an armature pivoted to the free end of said heel piece and extending toward the other end of said core, said armature adapted to actuate 90 said springs, an armature extension pivoted to the end of said armature and extending substantially at right angles to said armature and core, non-magnetic material cooperating with the end of said core to form a 95 plane surface, and a roller on said extension bearing against said plane surface.
- Signed by me at Chicago, Cook County, State of Illinois, this 11th day of March, 1919.
- JOHN ERICKSON.
